(57) **CLAIM**

The ornamental design for a toy fire truck, as shown and described.

DESCRIPTION

FIG. 1 is a perspective view of a toy fire truck; FIG. 2 is a right side view of the toy fire truck of FIG. 1, and the left side view of the toy fire truck is a mirror image of FIG. 2;

FIG. 3 is a front view of the toy fire truck of FIG. 1;

FIG. 4 is a back view of the toy fire truck of FIG. 1;

FIG. 5 is a top view of the toy fire truck of FIG. 1; and,

FIG. 6 is a bottom view of the toy fire truck of FIG. 1. The broken lines in FIGS. 1-6 represent environment only and form no part of the claimed design.
